DESIGN FOR A SHELVED TABLE

Lee L. Woodard, Owosso, Mich.

Application November 10, 1937, Serial No. 72,769

Term of patent 3½ years

To all whom it may concern:

Be it known that I, Lee L. Woodard, a citizen of the United States, residing at Owosso, county of Shiawassee, State of Michigan, and whose post office address is #825 W. Oliver Street, in said city, have invented a new, original, and ornamental Design for a Shelved Table, of which the following is a specification, reference being had to the accompanying drawing constituting a part there-of.

In the drawing:—

Fig. 1 is a perspective view from one side of a shelved table showing my new design.

Fig. 2 is a perspective view from the other side thereof.

I claim:—

The ornamental design for a shelved table, substantially as shown.

LEE L. WOODARD.
